UNITED STATES PATENT OFFICE.

ERNST OTTO GOTTSCHALK, OF DRESDEN, GERMANY.

DISPENSING CLOSURE FOR BOTTLES AND THE LIKE.

Application filed May 25, 1927, Serial No. 193,996, and in Germany February 6, 1926.

My invention relates to dispensing closures for bottles and other hollow vessels such as are used for perfumes, cosmetic liquids and the like, and has for its object to 5 provide an improved closure of simple construction which can be readily moved from the closed to the dispensing position and vice-versa.

The invention comprises a cap, a revoluble 10 cover fitted thereon, and a closing member pivotally mounted between the cover and the cap, the closing member being preferably formed in the shape of a bell-crank lever. At the point of intersection between the 15 two arms of the lever is formed an outwardly extending hemispherical projection, with a flat member surrounding the projection and adapted to bear against the cap. Central openings are provided in the cap 20 and cover in registry with each other for the passage of the material to be dispensed. One of the two arms of the bell-crank lever is provided with a hole for the reception of a pivot which extends outwardly from the 25 cap, and the other arm has a hole for the reception of a pivot which extends inwardly from the cover, so that when the cover is rotated the projection on the bell-crank lever is turned to open and close the discharge 30 openings in the cover and cap.

A form of embodiment of the invention is illustrated by way of example in the accompanying drawing.

Fig. 1 is a sectional view of the cap,

Fig. 2 is a plan view of the same,

Fig. 3 is a sectional view of the cover,

Fig. 4 is a plan view of the same,

Fig. 5 is a plan view of the closing member,

Fig. 6 is a section on the line 6—6 of Fig. 5,

Fig. 7 is a section on the line 7—7 of Fig. 5,

Fig. 8 is a sectional view of the assembled closure when in dispensing position,

Fig. 9 is a plan view of the same,

Fig. 10 is a sectional view of the closure when in closed position, and

Fig. 11 is a plan view of the same.

The closure comprises a cap A adapted to fit over the neck of a bottle or the like, a cover B rotatably fitted over said cap, and a closing member C interposed between the cap and the cover. The cap A is provided 55 with a peripheral boss q, and with a de-

pressed or insert portion n, in which is formed, by stamping or otherwise, an outwardly extending pivot member d, spaced from the center of the inset portion n. A discharge opening e is centrally positioned in said cap and is surrounded by an integrally formed annulus f, which may be slightly offset from the remainder of the inset portion n. The cover B is also provided with a central discharge opening g, the edges of which are pressed inwardly into a frusto-conical shape and thus suitably stiffened. The cover B also has a pivot member h, spaced from the central discharge opening g and formed by stamping or pressing the material of the cover inwardly. The closing member C, as shown in Fig. 5, is shaped like a bell-crank lever and has at the intersection of its two arms an outwardly extending hemispherical projection i and an offset annulus k surrounding said projection. In one arm of the bell-crank lever is formed a hole l adapted to receive the pivot member d, and in the other arm is formed a larger hole m adapted to loosely receive the pivot member h, for a purpose to be described.

The closing member C is rotatably supported by means of the hole l on the pivot B in such a manner that the annulus k engages and registers with the annulus f when the closure is in closed position. The pivot member h of the cover rests loosely in the larger hole m of the closing member C. The edge p of the cover B is turned downwardly and inwardly over the peripheral boss q of cap A so as to rotatably secure the cover to the cap.

The operation of the device is as follows. When cover B is rotated in the counterclockwise direction the closing member C will be turned to the open or dispensing position shown in Figs. 8 and 9, whereupon the contents of the vessel may pass out through the openings e and g. When it is desired to bring the closure to the closed position shown in Figs. 10 and 11, the cover B is rotated in the clockwise direction, whereupon the closing member C will be turned by the pivot h of said cover, the loose fit of the pivot in the hole m being provided to permit this action. Thus the hemispherical projection i of the closing member C will be moved until its seats in the discharge opening g of the cover, the cam action of projection i against the frusto-conical edge of 110

opening *g* causing the cover *B* to raise in such a manner that it is elastically deformed and presses the annulus *k* tightly against the similar annulus *f*, thereby tightly closing the discharge hole *e*.

I claim:

1. A dispensing closure for bottles and the like comprising an apertured cap adapted to fit over the mouth of a bottle, a cover 10 rotatably secured to said cap and having a discharge opening registering with the aperture in said cap, the edges of said opening being turned inwardly, and a closure member interposed between said cap and said 15 cover and pivoted to said cap, said closure member being provided with a projection constructed and arranged to seat in said

opening and being provided with a portion adapted to close the aperture in said cap.

2. A dispensing closure for bottles and the like comprising an apertured cap adapted to fit over the mouth of a bottle, a cover 20 rotatably fitted over said cap and having a discharge opening registering with the aperture in said cap, and a closure member pivoted at spaced points to said cap and said cover and adapted to be moved, by rotation of said cover, to open and closed positions and being adapted to close the aperture in said cap when moved to closed position.

25 In testimony whereof I have affixed my signature.

ERNST OTTO GOTTSCHALK.
